(57) **CLAIM**

The ornamental design for a combination vehicle-mountable radio transceiver and antenna, as shown and described.

DESCRIPTION

FIG. 1 is a perspective view of the combination vehicle-mountable radio transceiver and antenna;

FIG. 2 is a front elevation of the combination vehicle-mountable radio transceiver and antenna shown in FIG. 1; FIG. 3 is a rear elevation of the combination vehicle-mountable radio transceiver and antenna shown in FIG. 1; FIG. 4 is a left side elevation of the combination vehicle-mountable radio transceiver and antenna shown in FIG. 1; FIG. 5 is a right side elevation of the combination vehicle-mountable radio transceiver and antenna shown in FIG. 1; and,

FIG. 6 is a top plan view of the combination vehicle-mountable radio transceiver and antenna shown in FIG. 1. The broken lines shown in the drawings are for purposes of illustrating portions of the combination vehicle-mounted radio transceiver and antenna that form no part of the claimed design.
